ABRASIVE DEVICE

Application filed December 31, 1928. Serial No. 329,410.

The present invention relates to abrasive devices, and is particularly concerned with the provision of devices for finishing and smoothing operations.

5 In the finishing or smoothing operation on automobile bodies or the like, it is important that the abrasive device used shall have no exposed parts which are capable of scratching or marring the work, and it is also important that the abrasive pad shall have the exact 10 degree of flexibility for the particular coat of paint or varnish which has just been applied.

It is difficult to appreciate the importance 15 of this precise degree of flexibility in the supporting pad, except by actual practice, but it is found that a smoothing operation which might otherwise take fifteen or twenty minutes with a pad that is too soft may be accomplished with a pad of proper flexibility and hardness in a very small fraction of that time. On the other hand, if the pad is too 20 stiff or hard, too much material will inevitably be removed from spots, and it may even be necessary to repaint or revarnish the work. The relative hardness of a coating 25 varies with the thickness of the particular coat and the drying conditions to which it has been subjected up to the time of the smoothing operation.

As a specific example of a smoothing operation where the degree of flexibility is very important factor, the case of smoothing down what is commonly known in the parlance of those skilled in the art as an "orange peel", will be described hereinafter.

An "orange peel" may be formed where the paint or varnish has run or has been applied in overlapping coats, and this portion of the coating may be extremely hard so that a soft pad will scarcely "touch" it, or it may be so soft that a stiff pad will cut through it at once, marring the work and removing too much of the coating, so that retouching or repainting is necessary.

This relative hardness or softness of the "orange peel" depends on the conditions at the time of its formation, length of time of drying, thickness, etc., and its characteristics are readily ascertained by one skilled in the

art, by inspection, and a light application of the abrasive disc with the smoothing compound used. A skilled operator may then adjust the flexibility of the pad to the required degree dictated by his experience, and the 55 smoothing operation may be accomplished successfully and with a minimum expenditure of time.

One of the objects of the invention is the provision of an abrasive pad in which the 60 stiffness, hardness and flexibility may be varied to suit the needs of the work in order to prevent marring, and to expedite the smoothing operation.

Another object is the provision of a peculiarly simple and effective abrasive covering for a pad which is capable of use on both sides, and which is so cheaply constructed that the whole covering may be thrown away when the abrasive is incapable of further use. 65

Another object is the provision of a simple and effective abrasive disc for pads, which is reinforced and supported by fabric in such manner that the entire working surface of the disc may be used and there are no projecting parts near the disc which might mar or scratch the work. 75

Another object is the provision of an abrasive covering for pads, including a cloth for covering the edge of the pad for use in buffing or cleaning small areas during the smoothing operation when it is desired to clean the surface free of smoothing compound for the purpose of examining the work. 80

Other objects and advantages of the invention will be apparent from the following description and from the accompanying drawing, in which similar characters of reference indicate similar parts throughout the several views. 85

Referring to the drawing, of which there is one sheet;

Fig. 1 is a rear view of a portion of our abrasive device;

Fig. 2 is a middle sectional view of the 90 same;

Fig. 3 is a front view, partially broken away at a plurality of points, to show the different layers of the abrasive device.

The abrasive device of the present invention 100

tion preferably includes a covering member indicated in its entirety at 10, and a supporting member or disc indicated in its entirety at 11, and supporting member 11 may be embodied in many different forms, while still utilizing the important features of this invention. The supporting member 11 preferably has the property of flexibility, so that the portions near its periphery may be bent to conform to the surface of the work, and the supporting member should also be resilient and adapted to give locally, like a pad of felt, rubber or the equivalent.

One form of the supporting pad 11 is shown in Fig. 2 and this pad includes a hub 12 provided with a supporting flange 13 carrying a supporting disc 14. The hub 12 may be provided with a threaded bore 15 for securing the hub to an arbor, and with a counterbore 16 forming an annular shoulder 17 for determining the final position of the hub on the arbor.

The supporting disc 14 is secured to the hub 12 by a plurality of rivets 18 and the supporting disc 14 carries a disc 19 of felt or other flexible material secured to the metal disc 14 by a plurality of rivets 20. The felt disc 19 is in turn secured to a felt pad 21 by an annular row of stitching 22 and the felt pad 21 covers the entire forward surface of the supporting member 11, enclosing and protecting the heads of the rivets 20, and it will thus be observed that the felt pad 21 is secured to the hub and metal disc 14 without having any metal parts on the forward surface of the felt pad.

The felt disc 19 and felt pad 21 are adapted to give locally over any small area and to provide a resilient backing for the abrasive covering 10, and both of these felt members are also adapted to flex backward to conform to the surface of the work when pressure is applied to the rotating member by the operator. The metal disc 14 may have its outer edge curved backward as at 23 to permit a greater flexing movement of the felt pad 21 and to prevent the edge from cutting into the felt disc 19.

The abrasive covering 10 is preferably so cheaply constructed that when its abrasive surface is no longer capable of use, the entire covering may be thrown away without serious loss, and for this purpose I provide a circular piece of fabric 24 such as cambric, the outer edge 25 of which is protected by buttonhole stitching or any other economical form of binding.

In order that the one piece of cloth may give a maximum of service, and to give the required degree of stiffness, we provide both sides of the cloth 24 with a circular piece of abrasive material 26 and 27 such as sand or emery paper or cloth or the like, and the abrasive discs 26 and 27 are cemented to the cloth 24 by a cement which is not affected by mois-

ture or the smoothing liquid used in automobile finishing.

The cloth 24 reinforces and supports the abrasive discs 26 and 27, and both sides of the abrasive covering 10 may be used, so that a double service covering is provided.

The abrasive discs 26 and 27 are preferably of substantially the same diameter as the felt pad 21, so that the cloth 24 may be drawn back over the pad 21 and secured by a tension member 28. The tension member 28 consists of a cord which is threaded alternately from side to side through the cloth 24 about its periphery, and when the cord 28 is drawn tight on the back of the felt pad 21, the abrasive covering 10 is securely fastened on the pad.

It should be noted that the outer edge of the pad 21 is covered by cloth so that if the operator desires to momentarily clean a portion of the working area, he can do so by merely touching the cloth edge against the work so that he can see the work free of the smoothing compound, and then proceed to correct any defects which he may have observed.

One of the most important features of the present invention is the provision of a flexible and resilient abrasive device having means for varying the degree of flexibility or hardness of the pad, and this may be accomplished by providing a plurality of flexible, yet slightly stiff discs of celluloid, isinglass or the like, between the pad 21 and the abrasive covering 10. The celluloid discs 29 also protect the pad from the smoothing compound or liquid, and as previously described, these discs may be removed or inserted to change the flexibility and hardness of the whole pad. For very soft coatings of paint or varnish, most of the discs 29, or all of them, may be omitted and the pad is thereby given a softness and flexibility which is perfectly adapted for use on the softest paint coating which any operator may encounter, but where the "orange peel" is unusually hard, the operator may quickly untie the cord 28 and insert a plurality of the discs 29 to give the pad the required hardness and stiffness necessary to smooth down the "orange peel" quickly.

The operating time in a particular case may be reduced to one-twentieth of the time which would be required if the flexibility of the pad could not be changed to suit the conditions, and at the same time the operator is enabled to use the same pad on work which requires a very soft and flexible pad.

The celluloid discs 29 are flexible and capable of bending with the pad, but the addition of each celluloid disc reduces the flexibility by a slight degree, and if enough discs are employed, the pad becomes quite stiff. The celluloid discs also adjust the relative hardness of the pad because they distribute the pressure over a larger area of the pad, and

thereby prevent the pad from giving locally as the otherwise soft felt pad would do.

It will thus be observed that we have invented an abrasive device which is peculiarly adapted to be used efficiently on all kinds of smoothing work, and particularly on automobile bodies. Our abrasive device includes means for adjusting the flexibility and the relative hardness or softness of the pad, as well as a novel and economical form of the abrasive covering capable of giving double service, and so cheaply constructed that the entire covering may be thrown away when the abrasive surface is no longer capable of use.

Our abrasive device has no projecting parts or metal adjacent the working surface which might mar the work and the entire structure is peculiarly simple and sturdy and capable of long and efficient service.

While we have illustrated a preferred embodiment of our invention, many modifications may be made without departing from the spirit of the invention, and we do not wish to be limited to the precise details of construction set forth, but desire to avail ourselves of all changes within the scope of the appended claim.

Having thus described our invention, what we claim is new and desire to secure by Letters Patent of the United States, is:

An abrasive device, comprising a supporting hub, a resilient and flexible pad carried by said hub and adapted to flex relative to said hub, a plurality of thin and flexible discs located on the face of said pad for providing said pad with a predetermined degree of flexibility and local resiliency, a covering for said pad and discs comprising an abrasive member enclosing said discs and pad, and means for securing said covering to said pad adjacent the outer edge of said pad to permit said pad to flex freely under pressure applied to said abrasive device.

In witness whereof, we hereunto subscribe our names this 17 day of Dec., 1928.

FRANS O. ALBERTSON.
GUSTAV A. OLSEN.
